UNITED STATES PATENT OFFICE.

BRYANT BANNISTER, OF PITTSBURGH, PENNSYLVANIA.

EXPLOSION-ALLEVIATOR FOR INTERNAL-COMBUSTION ENGINES.

1,360,075.

Specification of Letters Patent. Patented Nov. 23, 1920.

Original application filed February 25, 1920, Serial No. 361,225. Divided and this application filed July 26, 1920. Serial No. 399,127.

To all whom it may concern:

Be it known that I, BRYANT BANNISTER, a citizen of the United States, and resident of Pittsburgh, in the county of Allegheny and State of Pennsylvania, have invented a new and useful Improvement in Explosion-Alleviators for Internal-Combustion Engines, of which the following is a specification.

10 This invention relates to an explosion alleviator for internal combustion engines, and is a division of copending application, Serial No. 361,225, filed February 25, 1920.

One object of the invention is to provide 15 mechanism for use in conjunction with internal combustion engines, which renders possible the employment of a high compression without the occurrence within the cylinder of a correspondingly high explosion 20 pressure at any instant.

Another object of the invention is to provide means which smooth out the high pressure impulse incident to the explosion of the combustible charge, over an increased portion 25 of the power stroke of the engine piston; thus not only damping the sharp initial rise in pressure during combustion of the charge, but also preventing the usual abrupt drop in pressure during expansion.

30 A further object of the invention is to provide valve means which serve to secure the full effect of the pressure alleviation and conservation by operating with sufficient speed after ignition of the combustible charge to permit expansion into an auxiliary clearance space during the progress of combustion.

40 A practical advantage derived from the foregoing is that internal combustion engines may be readily modified so as to materially increase compression, and secure a substantial gain in available power and in economy, without greater stress in, or shock to, the engine parts. Thus by decreasing the 45 clearance space within the cylinder, or cylinders, of the engine, or by increasing the piston displacement without increasing the volume of the clearance space, a compression ratio of four to one and greater may be obtained without increasing the strength of the cylinder head, cylinder walls, or moving parts.

Further practical advantages derived

from use of the device, are increased power and torque, and increased flexibility of operation.

It is, of course, possible to allow the compression ratio to remain as before and to secure economy in manufacture by lessening the amount of metal in the cylinder, or cylinders, of the engine to which the device is applied.

In the accompanying drawings Figure 1 is a vertical sectional view of the explosion alleviator; Fig. 2 is a view of the valve units connected to a common auxiliary clearance chamber, one unit being shown in plan and the other being shown in horizontal section; and Fig. 3 is a vertical sectional view showing the explosion alleviator on a reduced scale and illustrating operating connections for the valve means of the alleviator.

The device of the present invention is shown in conjunction with the cylinder, or cylinders, of an internal combustion engine; 75 and is arranged to communicate with the clearance space of such cylinder or cylinders. With reference particularly to Fig. 1 of the drawings, the numeral 1 designates an auxiliary clearance, or expansion, chamber 80 which communicates with the interior of the cylinder by way of a passage 2. Controlling passage 2 from the cylinder clearance is a valve 3 having a seat 4 within the passage.

The specific functional idea of the explosion alleviator is to open communication between the clearance space in the cylinder and the auxiliary clearance shortly after ignition and before combustion is complete, thereby permitting the combustion products 90 to expand into the auxiliary clearance and damp the initial explosive force following upon ignition; to maintain the valve open throughout a portion of the power stroke so that pressure built up in the auxiliary clearance may operate upon the cylinder piston during a portion of the expansion stroke therein; and to maintain the valve controlling communication between the cylinder clearance and the auxiliary clearance closed 100 during the latter part of the expansion stroke and during the exhaust, intake, and compression strokes, so that the space into which the combustible charge is compressed is no greater than is normal with the cylinder itself.

- It is necessary, in order to obtain a smooth distribution of explosive force, that the valve should be maintained in its open position during a sufficient portion of the power stroke to permit pressure, which has been built up in the auxiliary clearance during combustion to do work upon the engine piston as pressure within the cylinder tends to drop.
- 10 It is necessary that the valve means controlling communication between the clearance space of the cylinder and the auxiliary clearance be opened quickly at the proper instant. It is obvious that if the valve is not lifted before the combustion in the cylinder is complete, the auxiliary clearance loses all valuable function. It is therefore requisite that the valve be lifted from its seat within a few ten thousandths of a second following the instant of ignition.
- 15 It is also necessary that the valve be returned to its seat promptly when the pressure within the auxiliary clearance has performed its function, and that it remain closed during the compression stroke in the cylinder. Otherwise ignition would be communicated to a combustible charge within the auxiliary clearance upon ignition of the charge in the engine cylinder.
- 20 30 The valve 3 is provided with a valve stem 5, preferably provided at its lower extremity with a roller 6. Against the lower extremity of valve stem 5 bears a cam 7 on a cam shaft 8.
- 35 The cam shaft 8 may be actuated by any suitable connection with the crank shaft of the engine to which the device is applied, or by any other suitable timed actuating means.
- 40 It will be understood that the cam must be designed and the timing be such that the valve is lifted substantially instantaneously upon ignition in the engine cylinder. The design of the cam is such that it will maintain the valve open during the desired portion of the power stroke in the cylinder.
- 45 Against a suitable collar 9 on valve stem 5 bears a helical spring 10, which exerts a force tending to maintain the valve in seated position. When the high, or inoperative, portion of the cam passes out of contact with the lower extremity of the valve stem, the spring 10 serves to return the valve promptly to its seat. Obviously, spring 10 must be of sufficient strength to maintain the valve 3 in seated position during the compression stroke in the engine cylinder.
- 50 Fig. 3 of the drawings illustrates convenient means for operating the cam shaft 8, which carries the cam 7 for producing the timed lifting of the valve 3. Such means comprise a gear 12 on cam shaft 8 and meshing with a gear 13 on the main cam shaft of the engine. Obviously the operation of the cam shaft 8 may be secured by various actuating means and connections adapted to

varying forms of internal combustion engine in conjunction with which the alleviator is employed.

The auxiliary clearance chamber is preferably provided with a heat insulating lining 11, so that loss of heat, due to this increased radiating surface, is minimized. As shown in Fig. 2 of the drawings, the auxiliary clearance chamber is preferably made common to all the cylinders of an engine, when the engine to which the device is applied is of the multi-cylinder type. In such case, the auxiliary clearance has a valve controlled communication with the clearance space of each of the cylinders.

When the cam functions, lifting the valve after ignition in the engine cylinder, gases expand into the auxiliary clearance, further compressing any gas trapped in the auxiliary clearance upon previous closing of the valve. As the pressure within the cylinder drops during the power stroke in the cylinder, this pressure within the auxiliary clearance acts upon the piston in the cylinder to do work thereon, the valve remaining lifted during this interval. Spring 10 causes the valve to be reseated when the cam ceases to exert a positive upward pressure upon the valve stem. The timed relation between the cam shaft and moving parts of the engine must be such that the valve remains seated until after the ignition of the succeeding charge in the engine cylinder.

A number of modifications may be made in the form and arrangement of the auxiliary clearance and controlling valve, and also in the valve operating means and their connections without departing from the spirit of the invention. The scope of the invention is therefore to be restricted only to the limitations contained in the appended claims.

What I claim is:

1. In conjunction with an internal combustion engine an auxiliary clearance chamber in communication with the clearance space of a cylinder, normally seated valve means controlling such communication, and means actuated by the moving parts of the engine arranged to unseat the valve, after ignition in the engine cylinder and to maintain said valve unseated during a portion of the power stroke in the cylinder.

2. In conjunction with an internal combustion engine an auxiliary clearance chamber in communication with the clearance space of a cylinder, normally seated valve means controlling such communication, and mechanically operated means arranged to unseat the valve after ignition in the engine cylinder and to maintain said valve unseated during a portion of the power stroke in the cylinder.

3. In conjunction with an internal combustion engine an auxiliary clearance cham-

ber in communication with the clearance space of a cylinder, normally seated valve means controlling such communication, a cam arranged to act upon the valve means, and connections with the moving parts of the engine whereby said cam is caused to lift the valve after ignition in the engine cylinder and to maintain it unseated during a portion of the power stroke in the cylinder.

4. In conjunction with an internal combustion engine an auxiliary clearance chamber in communication with the clearance space of a cylinder, valve means controlling such communication, means actuated by the moving parts of the engine arranged to unseat the valve after ignition in the engine cylinder and to maintain said valve unseated during a portion of the power stroke in the cylinder, and resilient means arranged to exert a force greater than that caused by compression in the engine cylinder for normally maintaining said valve seated.

5. In conjunction with an internal combustion engine an auxiliary clearance chamber in communication with the clearance space of a cylinder, valve means controlling such communication, mechanically operated

means arranged to unseat the valve after ignition in the engine cylinder and to maintain said valve unseated during a portion of the power stroke in the cylinder, and resilient means arranged to exert a force greater than that caused by compression in the engine cylinder for normally maintaining said valve seated.

6. In conjunction with an internal combustion engine an auxiliary clearance chamber in communication with the clearance space of a cylinder, valve means controlling such communication, a cam arranged to act upon said valve means, connections with the moving parts of the engine whereby said cam is caused to lift the valve after ignition in the engine cylinder and to maintain it unseated during a portion of the power stroke in the cylinder, and resilient means arranged to exert a force greater than that caused by compression in the engine cylinder for normally maintaining said valve seated.

In witness whereof, I hereunto set my hand.

BRYANT BANNISTER.
